UNITED STATES PATENT OFFICE.

SUSAN TAYLOR CONVERSE, OF WOBURN, MASSACHUSETTS.

UNDERWAIST.

SPECIFICATION forming part of Letters Patent No. 513,633, dated January 30, 1894.

Application filed June 9, 1893. Serial No. 477,113. (No model.)

To all whom it may concern:

Be it known that I, SUSAN TAYLOR CONVERSE, of Woburn, in the county of Middlesex and State of Massachusetts, have invented 5 an Improved Underwaist, of which the following is a specification.

In the drawings: Figure 1 is a front view and Fig. 2 a rear view of one of my improved garments for women embodying all the features of my invention. Figs. 3 and 4 are like views of another form of my improved garment for children and men.

In the drawings A A' are pieces covering the breast and A² is a piece covering the portion of the back; that is the upper portion of the garment indicated by A A' A² covers the upper portion of the back and the breast; and this portion of the garment is of knitted fabric which is elastic as above explained; but 15 the parts A A' are connected by strips a a' of fabric which is inelastic, as any woven goods of proper quality and texture. The lower portion of the garment which extends about the body under the arms is also of woven fabric, or other fabric which is inelastic, and is 20 preferably made of six pieces b' b² b³ b⁴ b⁵ b⁶, to admit of a better fit around the body than a less number of pieces would give; but the 25 matter of main importance is that the garment 30 should be composed of an upper portion A A' A² of elastic fabric as above explained; a middle front portion a a' over the middle of the breast of fabric which is substantially inelastic; and a lower portion B which is also of 35 fabric substantially inelastic. A garment embodying this, the main feature of my invention, is not only comfortable to the wearer, but is especially well adapted to support the 40 lower garments, and distribute their weight in a very desirable manner, as the chest is allowed full expansion.

In most cases especially for women the lower portion B of the garment should be made adjustable as by lacing flaps d d' and cord d².

45 In Fig. 1, the middle front portion a a' is integral or otherwise connected with the front pieces b' b² and those front pieces b' b² are curved from under the arm scyes to the front and lower edge of the garment, and the pieces 50 b⁷ b⁸ are sewed to the lower curved edges of the pieces b' b². This construction is a fea-

ture of my invention and is especially desirable in women's garments which cover the abdomen.

In Fig. 1 the breast pieces A A' have gores 55 cut out from their lower edges, and the cut edges formed by cutting out these gores are sewed together and the seams are covered by the reinforcing strips a³. In most cases two gores and two strips a³ will answer, but for 60 very full busts three are better; and at times one will be sufficient. Of course for men and children these gores and strips a³ are unnecessary.

In practice I prefer to carry the reinforcing 65 strips a³ well above the seam joining the edges formed by cutting out the gores; and the strips a³ should be of inelastic fabric for the best results.

I am aware of Patent No. 376,924, to Emma 70 Thompson, dated January 24, 1888, and disclaim all that is shown in it, for the upper part of the garment there shown is composed of a back B, and shoulder straps e e, both of inelastic fabric, while in my garment the back 75 A² and the two front pieces A A' are of elastic fabric.

What I claim as my invention is—

1. The improved under waist above described composed of the upper pieces A A' A² 80 of elastic fabric, covering the upper portion of the back, shoulders and breast except at the front; middle front pieces b' b² of inelastic fabric with extensions a a' at their upper edges; back pieces b⁴ b⁶ of inelastic fabric and secured to the lower edge of back piece A²; and back pieces b³, b⁵ of inelastic fabric; all substantially as set forth.

2. An under waist composed of the upper pieces A A' A² of elastic fabric covering the 90 upper portion of the back, shoulders and breast, except at the front; middle front pieces b' b² of inelastic fabric with extensions a a' at their upper edges and cut curved at their lower edges; lower front pieces b⁷ b⁸ of inelastic fabric with their upper edges cut curved to fit the curves on the lower edges of the middle front pieces; and back pieces of inelastic fabric secured to the lower edge of the back piece A² and to the side edges of the front pieces b' b² b⁷ b⁸; all substantially as set forth. 95 100

3. A body garment for women composed of

an upper portion A A' A² of elastic fabric, except at the middle front part a a', which is of inelastic fabric, and with the front elastic pieces A A' gored out at their lower edges, 5 and provided with reinforcing strips a³ over the seam which unites the edges formed by cutting out the gores, this upper portion cov-

ering the back, shoulders and breasts; and of a lower portion B covering the body below the arms, all substantially as set forth.

SUSAN TAYLOR CONVERSE.
